AUTOMOBILE FENDER

Clifford C. Voss, Clawson, Mich., assignor to Chrysler Corporation, Highland Park, Mich., a corporation of Delaware

Application July 29, 1957, Serial No. 47,125

Term of patent 14 years

(Cl. D14—6)

FIG. 1

FIG. 2

FIG. 3

FIG. 4

Fig. 1 is a fragmentary side elevational view of an automobile fender showing my new design;

Fig. 2 is an end elevational view thereof;

Fig. 3 is a section taken on the line 3—3 of Fig. 1; and

Fig. 4 is a side elevational view of an automobile fender showing my new design.

The dominant features of my design reside in the portions shown by means of full lines in the drawing.

I claim:

The ornamental design for an automobile fender, substantially as shown and described.
